UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

MACHINE FOR OPERATING UPON CASTING-PATTERNS.

1,267,842.

Specification of Letters Patent. Patented May 28, 1918.

Application filed September 18, 1915. Serial No. 51,450.

To all whom it may concern:

Be it known that I, CHARLES C. BLAKE, a citizen of the United States, residing at Brookline, in the county of Norfolk and 5 State of Massachusetts, have invented a new and useful Improvement in Machines for Operating upon Casting-Patterns, of which the following is a specification.

The present invention relates to machines 10 for operating upon casting patterns, and more particularly to a machine for operating upon casting patterns which determine the form of the leaders used in automatic shoe machines.

15 These leaders comprise a sole-shaped body portion provided with a marginal flange the exterior face of which is beveled at the upper end thereof. The casting patterns for these leaders are now made by first producing 20 a sole-shaped blank having the shrinkage of cast iron and the spring of the last measurements incorporated therein, then inserting the blank into a machine provided with automatic mechanism for winding a strip of paper around the edge of the blank 25 to form a flange thereon, and then inserting the pattern, having the marginal flange thereon, into a machine which imparts the draft to the flange necessary for the removal 30 of the pattern from the sand. After the pattern is removed from this machine it is finished manually by removing the surplus stock at the upper end of the exterior face 35 of the flange to form the bevel, hereinbefore referred to, in the leader.

The object of the present invention is to produce a machine for removing the surplus stock from the casting pattern.

To the accomplishment of this object, and 40 such others as may hereinafter appear, the features of the invention relate to certain devices, combinations and arrangements of parts hereinafter described and then set forth broadly and in detail in the appended 45 claims which possess advantages readily apparent to those skilled in the art.

The various features of the present invention will be best understood from an inspection of the accompanying drawings 50 illustrating the best form of the invention at present known to the inventor, in which,

Figure 1 is a front elevation of the casting pattern beveling machine;

Fig. 2 is a plan;

Fig. 3 is a sectional front elevation; and 55

Fig. 4 is a sectional elevation of the casting pattern after it has been operated upon by the machine of the drawings.

The casting pattern which is to be beveled by the machine illustrated in the drawings 60 comprises a sole-shaped blank 1 (Fig. 4) provided with a marginal flange 2. The bottom of the flange is narrower than the top to provide for the draft which permits the withdrawal of the pattern from the 65 sand.

In the illustrated embodiment of the invention the pattern is supported upon the upper face of a stationary platen 3 secured to a bracket 4 carried by a column 5. In 70 order to feed the pattern over the platen the opposite side faces of the flange 2 are engaged by a pair of rolls 6 and 7 (Fig. 3). The rolls 6 and 7 are substantially frustoconical in shape in accordance with the 75 shape of the draft in the flange.

The roll 6 projects through a slot 7a in the platen 3 and is carried upon the upper end of a shaft 8 which is journaled in a sleeve bearing 9 pivoted at 10 on the bracket 4. 80 The lower end of the shaft 8 is provided with a gear 11 which meshes with a gear 12 on a vertical shaft 13 journaled in bearings in the bracket 4. The shaft 13 is driven through a worm gear 14 on the shaft which 85 meshes with a worm 15 (Fig. 2) on a horizontal shaft 16 one end of which is journaled in the column 5 and the other end of which is journaled in a bracket 17 projecting from the column. The shaft 16 is 90 driven from an electric motor 18 (Fig. 1) mounted in the base of the machine, by a belt 19 which passes over pulleys 20 and 21 secured to the shaft 16 and motor 18, respectively.

95 In order to maintain the roll 6 in operative position against the inside face of the flange 2 the sleeve bearing 9 is connected to one end of a rod 22 (Fig. 3) the other end of which slides loosely in a guideway 24 on 100 the bracket 4. Coiled around the rod 22 is a spring 25 which is interposed between the sleeve bearing 9 and the bracket 4. The inward movement of the roll 6 under the influence of the spring 25 is limited by a stop 105 26 on the sleeve bearing 9 which is arranged to engage a bridge 27 on the bracket 4. To withdraw the roll 6 from the flange the

sleeve bearing 9 is provided with an arm 28 which is connected by a rod 29 to a treadle 30 (Fig. 1).

The roll 7 is carried upon the upper end 5 of the shaft 13 (Fig. 3). With the construction so far described the rotation of the rolls 6 and 7 feeds the pattern over the platen and also swings the pattern during the feed to maintain the reversely curved portions of 10 the flange in proximity to the operating point in the line of feed. The roll 7 is dished upon its upper face 31 to permit the operation of a rotary cutter 32 close to the roll.

The cutter 32 is shaped like a bell and is 15 arranged with its cutting edge 33 in a vertical plane bisecting the axis of the roll 7 (Fig. 2). By employing a bell-shaped cutter and a feed roll, having its upper face dished on a curve concentric to the cutting 20 edge of the knife, a bevel 34 will be formed on the exterior face of the flange at the upper end thereof.

The cutter rotates in a contra-clockwise direction in order to form a clean cut on the 25 flange. By rotating the cutter in this direction there is a tendency for the cutter to lift the pattern from its support. To overcome this tendency a presser foot 35 is provided which engages the top face of the flange 30 close to the operating point. The foot 35 is carried upon a guard 36 which covers the cutter 32.

The cutter 32 is secured to one end of a horizontal shaft 37 (Fig. 2) which is driven 35 from the shaft 16 by a belt 38 which passes over pulleys 39 and 40 on the shafts 37 and 16, respectively. The shaft 37 is journaled in bearings 41 formed in a yoke 42 rising from a plate 43 which is supported on the platen 40 3. The plate 43 is arranged to slide over the platen 3 to shift the position of the cutter 32 laterally and thus vary its depth of cut. To this end the plate 43 is provided with a tongue 44 (Figs. 2 and 3) which slides in a 45 guideway 45 formed in the platen 3. The cutter 32 is shifted to vary its depth of cut by a bell crank lever 46, pivoted on the platen 3, one end of which is pivoted to the plate 43 and the other end of which is provided with an operating handle 47 (Fig. 1). To limit the extent of movement of the cutter the plate 43 is provided with stops 48 and 49 (Fig. 2) arranged to engage, one at a time, a lug 50 secured to the platen 3. The 55 stop 48 determines the position of the cutter when it makes its rough cut while the stop 49 determines the position of the cutter for its finishing cut. In order to hold the cutter in any of its positions of adjustment 60 a friction washer 51 is interposed between the plate 43 and the head of a bolt 52 secured to the platen 3.

To operate the machine the treadle 30 is depressed to separate the roll 6 from the roll 65 7. The pattern is then placed upon the

platen 3 with its exterior face positioned against the roll 7 and with the top of the flange positioned under the presser foot 35. The treadle 30 is then released to cause the spring 25 to press the roll 6 against the interior face of the flange. During the insertion of the pattern into the machine the stop 48 is in engagement with the lug 50 so that when the machine is started the cutter will make its rough cut upon the flange. Upon 70 starting the machine the rolls 6 and 7 will feed the flange past the rotating cutter and will swing the flange at the curves thereof to maintain the flange in proximity to the cutter 32 in the line of feed. After the point 75 of operation of the cutter has been transferred once around the flange the handle 47 is manipulated to shift the stop 49 into position against the lug 50 to position the cutter 32 for its final finishing cut.

It will be understood that, while it is preferred to employ the specific construction and arrangement of the parts shown and described, this construction and arrangement is not essential nor is the conjoint use of all 80 the features of the invention essential, except so far as specified in the appended claims, and it may be varied or modified without departing from the broader features 85 of the invention.

What is claimed as new, is:—

1. A machine for operating upon a pattern for casting leaders for use in automatic shoe machines having a marginal flange, having, in combination, means for resting 100 the pattern, and means for beveling the exterior face of the flange at the upper edge thereof, substantially as described.

2. A machine for operating upon a pattern for casting leaders for use in automatic 105 shoe machines having a marginal flange, having, in combination, means for supporting the pattern, means for beveling the flange, and means for relatively actuating the pattern and operating means to transfer the point of operation of the operating means around the pattern, substantially as described.

3. A machine for operating upon a pattern for casting leaders for use in automatic 115 shoe machines having a curved marginal flange, having, in combination, means for supporting the pattern, means for beveling the exterior face of the flange at the upper edge thereof, and means engaging the opposite side faces of the flange for feeding the pattern and swinging the pattern to maintain the flange in the line of feed, substantially as described.

4. In a machine for operating upon a pattern for casting leaders for use in automatic 125 shoe machines having a marginal flange, devices for supporting, guiding and feeding the pattern including operating means for beveling the exterior face of the flange at 130.

the upper edge thereof, substantially as described.

5. A machine for operating upon a pattern for casting leaders for use in automatic shoe machines having a marginal flange, having, in combination, a support for the pattern and a beveling knife relatively movable laterally to vary the depth of cut, and stops for limiting the extent of the relative 10 lateral movement of the support and knife, substantially as described.

6. A machine for operating upon a casting pattern having a marginal flange, having, in combination, a knife for beveling the 15 flange of the pattern, a laterally movable support therefor, and stops for limiting the extent of movement of the support, one stop determining the position of the knife in making its rough cut and the other stop 20 determining the position of the knife in making its finishing cut, substantially as described.

7. A machine for operating upon a casting pattern having a marginal flange, having, in combination, a support for the pattern, and a knife for beveling the flange on the pattern movable laterally from a position in which it makes its rough cut to another position in which it makes its finishing 30 cut, substantially as described.

8. A machine for operating upon a casting pattern having a marginal flange, having, in combination, a support for the pattern, a knife for beveling the flange on the pattern movable laterally from a position in 35

which it makes its rough cut to another position in which it makes its finishing cut, and stops for determining the extreme positions of the knife, substantially as described.

9. A machine for operating upon a casting pattern having a marginal flange, having, in combination, a support for the pattern, a slide carried thereby, a knife for beveling the flange on the pattern mounted on the slide, a handle for moving the slide 40 to vary the depth of cut of the knife, stops for limiting the extent of movement of the slide, and a friction device for holding the slide in adjusted position, substantially as described. 45

10. A machine for operating upon a casting pattern having a marginal flange, having, in combination, a support for the pattern, a rotary cutter for beveling the exterior face of the flange at the upper edge 50 thereof, and a roll having a face arranged to engage the exterior face of the flange and having a second face which is dished on a curve concentric to the cutting edge of the cutter, substantially as described. 55

11. A machine for operating upon a casting pattern having a marginal flange, having, in combination, a support for the pattern, a cutter for beveling the flange and rotating in a direction tending to lift the pattern from the support, and a presser foot arranged to engage the top of the flange to prevent the lifting of the pattern, substantially as described. 60 65
